Application June 30, 1943, Serial No. 492,896

15 Claims. (Cl. 197—20)

This invention relates to apparatus for transcribing onto a copy sheet, intelligence which has been previously recorded on a record strip, or tape; and it has for a broad object to provide apparatus of this type which is of improved construction and arrangement of parts.

In apparatus of the type referred to, it is customary to use a record strip on which code designations have been successively recorded and representing, respectively, according to a selected combinational code, the intelligence, or data, which it is desired to transcribe on the copy sheet. A typical example of apparatus of the character referred to, comprises a reading unit through which the record strip is fed and which includes a sensing mechanism operable to sense successively the code designations on the record strip; and the apparatus also comprises a writing unit such, for example, as a typewriter including a platen for supporting a copy sheet, a plurality of character type operatively arranged with respect to the platen, and a plurality of character key members, or actuators, corresponding, respectively, to the type and adapted to effect operation of the latter. As the record strip is fed past the sensing mechanism and the code designations are successively sensed thereby, the sensing mechanism effects operation of the character key members corresponding to the designations sensed and thereby transcribes the recorded intelligence, or data, on the copy sheet. Provision is also made for controlling by corresponding code designations recorded on the record tape, the usual functional operations of the typewriter, such as spacing, case shifting, tabulating, carriage return, and back spacing, which are necessary to transcribe correctly the recorded intelligence. The typewriter also includes functional key members controlling, respectively, the functional operations of the typewriter, and, as in the case of a character code designation, when a functional code designation is sensed, the sensing mechanism controls the operation of the corresponding functional key member to effect the desired operation of the typewriter.

This invention has for a further object to provide apparatus of the character referred to, which is relatively simple in construction and which operates smoothly and effectively to transcribe correctly recorded data at a relatively rapid rate.

A still further object is to provide an improved reader-typewriter unit including simple and effective control mechanisms for stopping the tape feeding when certain of the functional code designations on the tape are sensed and for resum-

ing the tape feeding without delay, upon completion of the corresponding functional operation of the typewriter.

Other objects of the invention will be pointed out in the following description and claims and illustrated in the accompanying drawings, which disclose, by way of example, the principle of the invention and the best mode, which has been contemplated, of applying that principle.

10 In the drawings:

Fig. 1 is a plan view showing one preferred embodiment of an apparatus constructed in accordance with the present invention;

Fig. 2 is an enlarged fragmentary plan sectional view showing the mechanical working parts of the reader unit, which forms a component part of the preferred embodiment shown in Fig. 1; certain of the parts being broken away to illustrate the construction more completely;

15 Fig. 3 is a fragmentary vertical sectional view taken on the line 3—3 of Fig. 2;

Fig. 4 is a fragmentary vertical sectional view taken on the line 4—4 of Fig. 2, and illustrating the tape feeding mechanism;

20 Fig. 5 is a fragmentary vertical section through the reader unit and the section being taken at right angles to Figs. 3 and 4 and being indicated by the line 5—5 on Fig. 2;

Fig. 6 is a fragmentary vertical sectional view 25 taken on the line 6—6 of Fig. 2, and illustrating the clutch mechanism and its controlling magnet which function to connect the main operating shaft of the reader with a source of power;

Fig. 7 is a fragmentary vertical section taken 30 on the line 7—7 of Fig. 3 and showing the reader pins and the manner in which they control their respective contacts;

Fig. 8 is a transverse vertical sectional view 35 through a typewriter which forms another component part of the apparatus disclosed in Fig. 1, the section being taken on the line 8—8 of Fig. 1;

Fig. 9 is a fragmentary detail sectional view 40 illustrating the structure and operation of the back space key of the typewriter;

Fig. 10 is an enlarged fragmentary vertical sectional view taken in a plane parallel to the plane 45 of Fig. 8, and showing the key controlled mechanism of the typewriter for effecting case shifting;

Fig. 11 is a fragmentary plan view showing the 50 key levers and related parts which control the operation of the case shifting mechanism;

Fig. 12 is a detail sectional view taken on the line 12—12 of Fig. 10;

55 Fig. 13 is a fragmentary detail section illustrat-

ing the structure and operation of the tabulating key and its associated cam unit;

Fig. 14 is a fragmentary plan view showing certain mechanism located at the back of the typewriter and including the parts which function to effect tabulating and back spacing of the carriage;

Fig. 15 is a fragmentary vertical section taken on the line 15—15 of Fig. 14;

Fig. 16 is a fragmentary perspective view illustrating the mechanism for effecting carriage return;

Fig. 17 is an enlarged fragmentary vertical section showing more clearly the toggle mechanism which actuates the carriage return clutch;

Fig. 18 is a fragmentary detail view taken in a vertical plane and showing certain coacting elements which comprise a part of an automatic margin control for the typewriter, the parts being shown as they appear when looking from the back toward the front of the typewriter;

Figs. 19a and 19b are two parts of an electrical wiring diagram illustrating diagrammatically the various electrical instrumentalities of the apparatus and the circuit wires connecting them; and

Fig. 20 is a view showing a portion of a record tape bearing all of the code hole designations of a preselected combinational code.

Before considering in detail the construction and operation of the illustrated embodiment of the invention, it will be helpful to consider first one practical example of a preselected combinational code by means of which the intelligence, such for example, as a letter, which it is desired to transcribe can be recorded on a record strip or tape. In Fig. 20, a portion of a record tape 10 is shown, and punched in the tape are all of the code hole designations of a combinational six-hole code. The six code positions are indicated at both ends of the tape 10 by the reference numerals 1 to 6, inclusive, and each code designation is arranged in a vertical column or recording field, and opposite each field bearing a code designation and at the lower edge of the tape, is placed the particular character or typewriter function corresponding to the code designation in that field. The smaller holes 11 at the center of the tape 10 and within each of the several recording fields are for the purpose of feeding the tape lengthwise during the reading or sensing operation. The tape may be punched by any suitable means such for example, as by the typewriter controlled punch disclosed in my copending application Serial No. 492,895, filed concurrently herewith.

In Fig. 1 of the drawings, the reader unit 100 and the copy typewriter 200 which comprise the illustrated embodiment of the present invention, are each shown in plan and as being connected by an electrical cable RT containing the necessary individual circuit wires (not shown) for effecting operation of the apparatus. The reader 100 is enclosed within a housing 12 and is provided across its lower side, as viewed in Fig. 1, with a platform or tape table 13 across which the record tape 10 bearing the recorded intelligence is fed during operation of the apparatus. A spool 15 is supported at the right-hand side of the table 13. Before the beginning of an operation the record tape to be transcribed is wound about the spool 15. A second spool 16 is also provided at the left of the table 13 and, as will later appear, is rotated by a flexible belt 17 during operation of the apparatus, for the purpose of winding the tape 10 thereon after it leaves

the sensing station of the reader. The sensing station is indicated at 20 and, as will appear more fully hereinafter, the recording fields of the tape are successively sensed by sensing elements located at this point. A removable gate 21 is provided at the sensing station for properly positioning and holding the tape with respect to the sensing elements. The tape 10 is guided in its movement toward the sensing station by a suitable guide member 22 fixed to the top of the tape table 13.

At the right-hand side of the reader 100, are provided three electrical switches indicated at 24, 25, and 26, respectively. As will appear more fully hereinafter, the switch 24 is the power switch and when closed, connects a convenient source of alternating current with the motor for driving the reader unit and with the motor for operating the typewriter. The switch 25 is the start switch and when closed, starts the sensing and feeding of the tape and the automatically controlled operation of the typewriter key members. The switch 26 is the stop switch and when closed instantly stops the feeding and sensing of the tape and the controlled operation of the typewriter.

The typewriter 200 which is shown in plan in Fig. 1 and the detail construction thereof in Figs. 8 to 18, inclusive, is a well known commercial form of power-driven typewriter and will be described more fully hereinafter. In Fig. 1, the typewriter 200 is shown as comprising the usual keyboard 210 comprising the character keys 211 which operate corresponding type bars 212, and the functional keys which include the shift key 213, shift lock key 214, shift release key 215, the carriage return key 216, the back space key 217, and the tabulating key 218. The space bar is indicated at 223. The typewriter 200 also comprises the conventional rotatable platen 219 mounted on the typewriter carriage 220 and which supports a copy sheet indicated at 221 and on which the data recorded in the tape 10 is automatically typed. At the lower and left-hand side of the typewriter 200 as viewed in Fig. 1, is provided a power switch 224 which, when closed, like the power switch 24, connects a source of alternating current with the typewriter and reader motors. At the lower and right-hand side of the typewriter is mounted a start switch 225 and a stop switch 226 which function, respectively, the same as the switches 25 and 26 on the reader 100. Thus, the operation of the apparatus may be controlled from either the typewriter or from the reader. An insert switch 227 is also provided on the typewriter which, when open, prevents starting of the tape feeding and sensing mechanisms in the reader 100 and thereby eliminates control by the latter of the typewriter, so that the typewriter keyboard 210 can be operated manually without interference from the reader. The insert switch 227 will normally be closed, and will be opened when it is desired to type manually an insert in the data being transcribed; for example, when it is desired to type manually the name and address of the person to whom the transcribed copy is to be sent or any other data which will be of interest only to the recipient of the copy.

The detail construction of the reader 100 is shown in Figs. 2 to 7, inclusive. The reader comprises a reader motor RM suitably mounted therein and which operates continuously as long as either the power switch 24 or power switch 224 is closed. The motor RM is operatively connected by a suitable flexible drive belt 30 with a

power shaft 31, the latter being mounted for rotation within suitable bearings 32 mounted within a frame 33 which is bolted to the base 34 of the reader.

The reader 100 also comprises an operating shaft 35 which is aligned with the power shaft 31 and is supported for rotation within suitable bearings 36 carried by the reader frame 33. A clutch 37, under the control of a clutch magnet CM, is operable to connect and disconnect the operating shaft 35 and the power shaft 31. The operating shaft 35 effects the operation of the tape feeding and sensing means. A cycle of operation of the apparatus is effected during each revolution of the shaft 35; viz., the tape 10 is fed or spaced a distance sufficient to bring the next recording field of the tape into sensing position, such next field is sensed to determine the code designations therein, if any, and the typewriter is operated in response to the sensing of the code designations. As long as the shafts 31 and 35 are clutched together the cycles of operation are repeated and the typewriter continues to transcribe the recorded data.

Insofar as the present invention is concerned, any suitable form of clutch may be used to connect the shafts 31 and 35. The clutch 37 which is shown, is well known to those skilled in this art, it being substantially the same as that disclosed in the U. S. Patent No. 2,206,646, granted July 2, 1940. If desired, reference may be had to this patent for a complete showing of the structural details thereof. For the purposes of the present disclosure, it is believed sufficient to say that the clutch comprises a driving element in the form of a toothed wheel 40 fixed to the end of the power shaft 31, and a driven element in the form of a barrel 41 fixed to the shaft 35 and carrying a radially slidable clutch pawl 42. The barrel 41 is formed with a diametrically disposed slot 43 within which the pawl 42 is slidable mounted. To the outer end of the pawl 42 is fixed a tooth element 44 which, when the pawl 42 is moved radially inward, engages the toothed wheel 40 to provide the driving connection between the shafts 31 and 35. Normally, the pawl 42 is urged in a clutch engaging direction by a suitable spring mounted within the clutch barrel 41. A clutch releasing lever 45 also extends diametrically across the clutch barrel and at right angles to the slot 43 and is mounted for limited angular movement therein. The lever is provided with an outer extension 46 which, when intercepted and engaged by the outer end of one arm 47 of a rocking lever 48, is moved to move the clutch pawl 42 radially outward against the force of the aforementioned spring in the barrel 41 to disengage the clutch.

The clutch parts are shown in Figs. 2 and 6 in their declutched position which is the home or starting position of the reader. The rocking lever 48 is mounted on a stud 50 carried by a part of the frame 33 and includes a second arm 51 which carries at its outer end the armature 52 of the clutch magnet CM. When the clutch magnet CM is energized, the lever 48 is rocked counterclockwise, as viewed in Fig. 6, which moves the outer end of the arm 47 upward and thereby releases the outer extension 46 of the releasing lever 45, and the clutch spring within the clutch barrel 41 then moves the pawl 42 radially inward to engage the toothed wheel 40 in the manner explained above. When the clutch magnet CM is deenergized, a tension spring 53 rocks the lever 48 clockwise and moves the outer end of

the arm 47 into the path of the outer extension 46 of the lever so that the latter is engaged and moved to move the pawl outward to disengage the clutch.

In order to prevent rebound of the parts when the clutch is disengaged and in order to hold the operating shaft 35 in the home position, the clutch barrel 41 is also provided with an annular extension or collar 54 having a notch 55 formed therein which, when the clutch is disengaged, receives the outer end of an arm 56 of a detent lever 57. The detent lever 57 is also pivoted on the stud 50 and includes another arm 58 which is connected to the armature 52 by means of the tension spring 53 previously mentioned. Thus, the spring 53 serves the dual purpose of urging the arm 56 into engagement with the periphery of the collar 54 so that it will fit within the notch 55 in home position, and to urge the arm 47 into position to intercept the extension 46 of the pawl releasing lever 45 and thereby declutch the parts.

As stated above, during the first part of each revolution of the operating shaft 35, the tape is fed or spaced lengthwise to bring a new recording field into sensing position. The tape feeding mechanism is shown more clearly in Figs. 2 and 4, and comprises a cam 60 mounted on the operating shaft 35 and cooperating with a rocking lever 61 pivoted on a fixed stud 62 carried by the frame 33 and comprising a pair of arms 63 and 64. The cam 60 and lever 61 are shown in Fig. 4 in the starting or home position and are so constructed that when the cam 60 begins to rotate in a counterclockwise direction, it first engages the arm 63 to rock the lever 61 counterclockwise and then engages the other arm 64 to rock the lever 61 clockwise and return the same to the position shown. A link 66 is pivoted at its lower end to the outer end of arm 64 and extends upwardly therefrom and is pivoted at its upper end by a stud 67 with a second link 68. The link 68 is pivoted to a shaft 70 and extends outwardly therefrom to hold the link 66 in the upright position shown.

Also pivotally connected on the stud 67 is a feed pawl 71 which is held in operative engagement with a ratchet wheel 72 fixed to the shaft 70, by means of a tension spring 73 connecting outer extending arms of the pawl 71 and the link 68. A detent 74 is pivotally supported by a fixed stud 75 and is held in engagement with the teeth of the ratchet wheel 72 by means of a tension spring 76 and thereby serves to prevent reverse movement of the ratchet wheel 72 and shaft 70. From the above, it is apparent that when the clutch is engaged and the lever 61 is first rocked counterclockwise by the cam 60, the pawl 71 will be moved downwardly thereby and will rotate the ratchet 72 and shaft 70 counterclockwise; and, when the cam 60 rocks the lever 61 clockwise, the pawl 71 will be moved upward to engage the next tooth of the ratchet 72.

The shaft 70 is the tape feed shaft and is provided with a feed wheel 77 having radially extending pins 78 which are adapted to engage the feed holes 11 in the tape 10. Thus, when the feed shaft is partially rotated in the manner just described, the tape is fed to the left as viewed in Figs. 2 and 3, a distance equal to the width of a recording field. The belt 17 which rotates the spool 16 is driven from a pulley 19 fixed to the tape feed shaft 70.

The mechanism for successively sensing the recording fields of the tape comprises six sensing

pins S1 to S6, inclusive, there being one pin for each of the code hole positions, and the pins are arranged in a single plane extending at right angles to the direction of movement of the tape, and so that when the tape comes to rest at the end of a feeding operation, the upper end of each pin will be directly beneath its corresponding code hole position in the field of the tape then in position to be sensed. The pins are guided for vertical movement within aligned openings in spaced guide blocks 80 and 81, respectively, which are fixed to the frame 33. Corresponding guide openings are also provided in the table 13 and in the gate 21 which are aligned with the openings in the guide blocks so that during a sensing operation each pin can be moved upward and through the tape when there is a hole in the code position in the tape corresponding to such pin.

The six sensing pins are supported and operatively connected, respectively, at their lower ends to six pairs of spring blade contacts C1 to C6, inclusive. Each pair of the contacts comprises a fixed blade 82 and a movable spring blade 83 which extends outwardly and is connected at its outer end to the lower end of its related sensing pin. The construction is such that the spring blades 83 constantly urge their respective contacts into closed position and their related sensing pins upward as viewed in Figs. 3 and 7. Between sensing operations, the six sensing pins are held in home position, the position shown in Fig. 3, by the outer lateral edge 84 of a vane 85, which edge extends across the pins and within transversely aligned notches 86 provided, respectively, in the sides of the pins. The vane 85 is, in effect, a rocker arm pivotally supported on a fixed stud 87 carried by the frame 33 and constantly urged to move in a clockwise direction, as viewed in Fig. 3, by a tension spring 88. The vane 85 is provided at its center with a depending arm 89 which carries at its lower end a roller 90 held by the spring 88 in contact with the face of a cam 91 mounted on the operating shaft 35 of the reader. When the roller 90 is in engagement with the high point of the cam, the vane 85 is held in the position shown in Fig. 3 where the several sensing pins are held in their respective lower positions and the pairs of contacts controlled thereby are held open.

After the tape has been spaced by the feeding mechanism in the manner previously described and has come to rest with the new recording field above the sensing pins, the cam 91 will have rotated counterclockwise from the position shown in Figs. 3, 94° of a revolution. When the shaft 35 has rotated 114°, the roller 90 will begin to move inwardly from the high point of the cam 91, and the vane 85 will move in a clockwise direction due to the force of the spring 88. The sensing pins S1 to S6, inclusive, will also follow the end 84 of the vane 85 upward due to the spring force in their respective movable blades 83. If there be a hole in the code position of the tape immediately above a sensing pin, its movable spring blade 83 will continue to move the pin upward and through such code hole and to a point where the pair of contacts controlled thereby will close. If there be no code hole in the position above a sensing pin, the upper end of such pin will strike the tape and will be held thereby against further upward movement, and in the latter position its related pair of contacts are held open.

By way of example, Fig. 7 shows the relative position of the parts during the sensing of a record field bearing the code designation for the let-

ter "Y." Sensing pins S1, S3, and S5 have passed through code holes in the corresponding code positions in the tape, which as shown in Fig. 20 is the code designation for "Y," and their related contacts C1, C3, and C5 are closed. The sensing pins S6, S2, and S4 have been stopped in their upward movement by the tape and their related contacts C6, C2, and C4 are thereby held open.

From the foregoing, it is apparent that during a sensing operation the contacts C1 to C6, inclusive, are closed by their related sensing pins singly or in combination, depending upon the code hole designation in the record field of the tape being sensed. The sensing operation is terminated by the high point of the cam 91 engaging the roller 90 on the arm 89 and moving the vane 85 counterclockwise, as viewed in Fig. 3, so that the end 84 thereof engages again the lower ends of the notches 86 in the several sensing pins S1 to S6 inclusive, and thereby moves the latter downward to the position shown in Fig. 3, where the related contacts are held in open position. The sensing operation is completed and the vane 85 is restored to home position at approximately 346° of each revolution.

In order to provide for automatically stopping the reading and sensing operation when there is no tape at the sensing station, a seventh pin 94 is mounted for vertical sliding movement within aligned openings in the spaced guide blocks 80 and 81 and in the table 13 and gate 21 and is positioned so that it will engage the central portions of the tape. The lower end of the pin 94 is supported and operatively connected to the movable spring blade 85 carrying one of a pair of contacts 96. The blade 95 is normally urged upward by the spring force inherent therein, to open the contacts 96 and move the pin 94 upward. If there is tape at the sensing station, the upper end of the pin 94 engages the underside of the tape and the contacts 96 are held closed. This is the position of the parts shown in Fig. 7. When the tape runs out, the pin 94 moves upward and opens the contacts 96 which, as will later appear, deenergizes the clutch magnet circuit and thereby stops the feeding and sensing operation of the reader. In Fig. 3, no tape is at the sensing station and the pin 94 is shown in the upper position and the contacts 96 are open. The pin 94 is large enough in diameter so that the feed holes 11 in the tape will not affect its operation.

The sensing contacts C1 to C6, inclusive, control, respectively, the flow of direct current to six translator relays M1 to M6, inclusive, of a relay type of translator mechanism which is diagrammatically shown in Fig. 19a, and which will be described more fully hereinafter, in connection with the description of the complete wiring diagram shown in both Figs. 19a and 19b. At this point, it is sufficient to say that by energizing translator relays M1 to M6, inclusive, singly and in combination, due to the closing of their related contacts C1 to C6, inclusive, during the reading operation described above, a number of controlling circuit paths are selectively established, which, with one exception, actuate, respectively, related key members of the typewriter. The circuit path just noted as being the exception, functions when energized by the sensing of a predetermined stop code designation to stop the sensing and tape feeding operation of the reader in a manner which will also be described fully hereinafter.

A cam 102 is also fixed to the operating shaft

35 and controls through a pivoted follower 103 the operation of a pair of spring blade contacts 104. As will appear more fully hereinafter the contacts 104 control the flow of current from a source of D. C. current and through the contacts C1 to C6, inclusive, in parallel to their related magnets M1 to M6, inclusive. The contacts 104 can be termed the D. C. common contacts and are normally held open by their movable spring blade. The cam 102 so shaped and positioned on the operating shaft 35 that the contacts 104 are closed at 142° of a revolution which is after the time for closing the sensing contacts C1 to C6, inclusive, and are opened at 311° which is before the sensing contacts are opened by the vane 85. The purpose of the D. C. common contacts is to provide for simultaneously energizing and deenergizing the relays M1 to M6, inclusive.

A cam 106 is also fixed to the operating shaft 35 and controls through a pivoted follower 107 the operation of a pair of normally open spring blade contacts 108 which are herein termed the A. C. common contacts. As will appear more fully hereinafter, the current which flows through the controlling circuit paths previously mentioned as being established by the selective energization of the translator relays M1 to M6, inclusive, is A. C. current, and the cam 106 is so shaped that it connects the source of A. C. current with these circuit paths at a predetermined point in each cycle of operation. In the structure shown, the cam 106 effects the closing of the A. C. common contacts 108 at approximately 170° of each revolution and opens the contacts at 294°.

The detail construction of the typewriter is shown in Figs. 8 to 18, inclusive, and as stated previously, is a well known, commercial form of power driven typewriter. The structural features and principles of operation of this typewriter are fully disclosed in a number of U. S. patents, among which is Patent No. 1,777,055, granted September 30, 1930, which discloses the general principles of operation of the key levers and how they control through related cam units, the operation of the type bars. In view of the detailed description of the construction and operation of the parts given in the patent just mentioned, only a brief description will be given herein which will be sufficient to enable the present invention to be understood. Reference may be had to the aforementioned patent for further details.

As shown in Fig. 8, the character keys 211 are mounted, respectively, on key levers 228, the latter being pivoted on a rod 229 which is supported by a cross frame 230 rigidly mounted in the typewriter frame. Rotatably mounted in the base 231 is the power roller 232 which is rotated in the direction of the arrow by means of an A. C. motor, not shown in Fig. 8, but indicated diagrammatically at TM in Fig. 18b. When the machine is in use, the power roller rotates continually.

Cooperating with the power roller 232 are the cam units 233 which are pivotally mounted on rods 234 extending parallel with the power roller 232. There is a cam unit 233 associated with each of the key levers 228, and each of the cam units which is operated by a character key 211, is connected by a link 235 with a sub-lever 236 pivoted on rod 229. The sub-levers 236 are connected by links 237 to type bars 212 through the medium of toggles 238. The type bars 212 are pivoted in the usual type bar segment 239 and the latter is provided with a type guide 240 located in front of the platen 219. As stated pre-

viously, the platen is adapted to support the work sheet 221 and is rotatably mounted in the carriage 220, and the latter is supported for lengthwise movement on front and rear rails 241 and 242, respectively, by means of suitable anti-friction roller trucks. Springs 243 connected to a curved spring anchoring member 244 and to toggles 238, provide means for locking the toggles in their normal or inactive position shown in Fig. 8.

When any character key 211 is manually depressed, its related cam unit 233 is caused to operatively engage the power roller 232 in a well known way, thereby rocking the cam unit 233 clockwise or counterclockwise, according to whether the operative cam unit is pivoted on the left hand or right hand rod 234, respectively, as viewed in Fig. 8. The rocking of the cam unit 233 causes its link 235 to be drawn downwardly, thereby rocking the corresponding sub-lever 236 in a clockwise direction. This movement of the sub-lever 236, through the corresponding link 237 and toggle 238, causes the type bar 212 associated with the selected key to rock in a counterclockwise direction to effect the impression of the type upon the work sheet 221 wrapped around the platen 219. The type bar, near the end of its operating stroke, engages the usual universal bar 245 and causes the universal bar to move rearwardly and downwardly in Fig. 8 to space the carriage forward in a manner not disclosed in detail herein, but which is well known to those skilled in the art.

To each of the character key levers 228 is connected by a spring 246, an actuating solenoid 247 which, when energized, pulls its related key lever 228 downward to operate the related cam unit 233 and type bar 212 in the same manner as described above when the related key 211 is manually depressed. As will appear more fully hereinafter, the solenoids 247 are selectively energized by the A. C. controlling circuits previously mentioned as being selectively established by the energizing of the translator relays M1 to M6, inclusive.

As will be readily understood by those skilled in the typewriter art, one of the cam units 233 is operated by manually depressing the space bar 223 and its related key lever, and such cam unit 233 when operated effects the rearward movement of the universal bar 245 to space the carriage. The detail mechanism for effecting this operation has not been shown herein as it would be a needless duplication of drawing and description. A solenoid 247 is also provided for operating the key lever on which the space bar 223 is mounted. The latter solenoid is shown diagrammatically in Fig. 19b.

The segment 239 is mounted in a frame 249 which forms part of the type basket. The type basket is movably mounted in the framework of the machine for case shifting movement in a well known way and normally occupies an elevated position shown in Figs. 8 and 10 for the typing of the lower case characters. The shift mechanism for drawing the type basket downward to permit the printing of upper case characters is described in U. S. Patent No. 1,945,097, granted January 30, 1934, and is partly shown in Fig. 10.

Secured, respectively, to the back of the type basket frame 249 and on opposite sides thereof, are two brackets 250. The brackets 250 are connected by links 251 to the outer ends of lever arms 252, the latter being fixed respectively, on the ends of a transverse shaft 253 journaled in the

framework of the machine. Pivot on a stud 254 at one side of the machine is a lever 255 having two pins 256 and 257, engageable by the short arms of a T shaped lever 258, the latter being pivotally mounted at 223 on one arm 259 of a three-armed lever 260. The lever 255 is connected by a link 261 to the outer portions of one of the lever arms 252 and at points spaced from the connection of such arm and its link 251. The T-lever 258 has a stud 262 projecting into a slot formed in an arm 263 comprising an extension of the left-hand shift key lever 264 as viewed in Figs. 1 and 11. One arm of lever 260 is connected by a link 265 to a cam unit 266 which is controlled by the shift key lever 264 in substantially the same manner as cam units 233 are controlled by the key levers 228, described above.

The type basket is shifted downward to upper case position when the shift key 213 mounted on key lever 264 is moved downward and is returned to lower case position when the key is released and moves upward. It is, therefore, customary to hold the key lever 264 in its lower position while writing upper case characters.

When the shift key lever 264 is depressed, the T-lever 258 is elevated to bring one of the short arms thereof to a position to the left of the pin 256, this movement taking place before the cam unit 266 controlled by the key lever 264 is operationally connected to the power roller 232. When the cam unit 266 controlled by the shift key is operated, the link 265 is drawn downwardly thereby rocking lever 260 in a clockwise direction. This draws the T lever 258 to the right in Fig. 10, and thereby through the engagement of said T lever with the pin 256, rocking the lever 255 clockwise. Consequently, through the link connection 261, the lever arms 252 connected thereto and the shaft 253 are rocked in a counterclockwise direction, thereby pulling downward the links 251 which result in the type basket being drawn downward to upper case position.

As disclosed fully in the aforementioned U. S. Patent No. 1,945,097, when the key lever 264 is released so that it is returned upward to its normal position by the spring 267, the cam unit 266 is again actuated by the power roller so that the cam unit rocks in a counterclockwise direction, as before. When the key lever 264 is released and before the cam unit 266 is actuated, the arm 263 of the lever 264 moves downward and thereby permits the T lever 258 to move downward to bring the lower of its short arms to a position to the left of the lower pin 257. Consequently, when the cam unit 266 is rocked counterclockwise as just stated, the cam unit through the link 265 rocks the lever 260 clockwise, and the latter through the T lever 258 and pin 257, rocks the lever 255 counterclockwise. The lever 255, through the link 261, rocks the arms 252 and shaft 253 clockwise to return, through the links 251, the type basket to the lower case position shown in Figs. 8 and 10.

During the controlled operation of the typewriter by the sensing mechanism and the translator relays, the key lever 264 is pulled downward to shift the type basket to upper case position by the energizing of a solenoid 268 having an armature 269 pivotally connected to a latching lever 270 which is, in turn, connected at its upper end by a stud 271 fixed within an opening in the key lever 264 and projecting into a slot 272 formed in the latching lever 270. As will presently appear, the key lever 264 is locked down when it is shifted by the solenoid 268, and the key lever 264

is released to return the type basket to lower case position by the energizing of a second solenoid 273 which pulls down the shift-release lever 274 at the right of the typewriter. The solenoid 268 is energized as a result of sensing a shift code designation in the tape 10 and the solenoid 273 is energized as a result of sensing a release code designation (see Fig. 20).

When the typewriter is operated manually, the shift key 213 is depressed and released to shift the type basket to upper and lower case positions. The manually operable shift lock key or button 214 cooperates with the key lever 264 and latching lever 270 to lock the key lever 264 down in its upper case position when it is desired to type manually a substantial number of upper case characters. When the key lever 264 is locked down, it may be manually released by depressing the shift-release key 215 and its associated key lever 274.

The shift latching lever 270 is arranged on one side of the key lever 264 and the shift-lock button 214 on the opposite side thereof. The shift-lock button 214 is provided with a vertical slot 275 also receiving the stud 271 projecting from the lever. A detent 276 is fixed to a stationary portion 277 of the typewriter frame and cooperates with the latching lever 270 in locking the key lever 264 down in shifted position. With the parts in their normal lower case position, as shown in Figs. 10, 11, and 12, the detent 276 engages the lowermost inner surface of the lever 270. A tension spring 278 connects the latch lever 270 with the shift key lever 264 and serves to hold the lever 270 in this position, the stud 271 extending from the lever 264 occupying the lower part of the slot 272. The shift lock button 214 is provided with a pin 279 which extends over the latching lever 270 and engages the top of the latter. With the parts in normal lower case position, the lever 270 supports the button 214 through the pin 279 and the stud 271 also occupies the lower part of the slot 275 in the button 214. The button 214 is also provided with spaced tabs 280 and 281, engaging respectively, the upper and lower sides of the lever 264 which aid in holding the button 214 in an upright position.

When the solenoid 268 is energized, the latching lever 270 is pulled downward thereby until the top of the slot 272 engages the stud 271 and then the key lever 264 will also be pulled down to actuate the cam unit 266 to shift the type basket to upper case. When the latter happens, the detent 276 will have cleared a ledge portion 282 on the lever 270 and the spring 278, in conjunction with the off-center pivotal connection between the armature 269 and lever 270, will move the lever 270 to the right or counterclockwise as viewed in Fig. 10, until the ledge 282 is under the fixed detent 276, thus locking the latch lever 270 and key lever 264 down in its shifted position.

When the button 214 is manually depressed, it also moves the latching lever 270 downward, through the pin 279, until the top of the slot 272 in lever 270 engages the stud 271 on key lever 264 and then the lever 264 will be moved downward with the lever 270 a distance sufficient to actuate the cam unit 266. When the latter occurs, the detent will have cleared the ledge portion 282 and the spring 278 will move the lever 270 counterclockwise, until the ledge 282 is under the detent 276, thus manually locking the latch lever 270 and key lever 264 down in shifted position.

As stated above, the key lever 264 is released to return to lower case position by energizing the

solenoid 273 or by depressing the shift-release key 215. To this end, a ball lever 284 is provided which comprises a pair of end plates 285 and 286 connected by a ball road 287. The ball lever 284 is mounted for pivotal movement by studs 288 and 289 extending outwardly from the plates 285 and 286, and journaled, respectively, within opposite sides of the typewriter frame. A stud 290 extends inwardly from the end plate 286 and within a notch 291 formed in a downwardly extending projection of key lever 274 on which the key 215 is mounted (see Fig. 8). A second stud 292 extends inwardly from the end plate 285 and over the outer end 293 of latching lever 270. Thus, when the lever 274 is moved down by the energizing of solenoid 273 or by manually depressing the key 215, the ball lever is rocked about its pivotal support and the stud 292 engages the end 293 of latching lever 270 and thereby rocks the latter downward and clockwise to move the ledge portion 282 out from under the detent 278 which unlatches the lever 270. When the lever 270 is thus released, the lever 284 is permitted to move up under the force of its spring 267 to the normal lower case position shown in Fig. 10.

The mechanism for back spacing the typewriter carriage is disclosed in Figs. 9 and 14, and operates in the same manner as the construction disclosed fully in U. S. Patent No. 2,873,553, granted August 23, 1932. In Fig. 9 herein, the back space key 217 is shown as mounted on a key lever 296 which is pivoted on the rod 229. A solenoid 297 is connected by a spring 298 to the key lever 296. When the solenoid is energized as a result of the sensing of a back space code designation in the tape, the lever 296 is pulled downward to operate a cam unit 299, similar in construction and operation to the cam unit 233 shown herein in Fig. 8 at the left of the power roller 233. When the cam unit 299 is operated, it pulls down a link 300 connected to one end of a rock lever 301 which is pivotally supported on the rod 229. The other end of rock lever 301 is connected by a link 302 (see also Fig. 14) to one arm of a bell crank 303 pivotally mounted on the rear fixed rail 242. The other arm of the bell crank 303 is connected by a link 304 to a pivoted dog 305 having a tooth 306 formed on its outer end and adapted to engage with the teeth of the escapement rack 307 mounted on the carriage 220. As is explained fully in the aforementioned U. S. Patent No. 1,873,553, when the bell crank 303 is rocked clockwise, as viewed in Fig. 14 herein, the link 304 moves the dog 305 clockwise and at the same time downwardly and into engagement with the teeth of the rack so that the carriage 220 is moved to the right, or backward, one space. Suitably mounted on the back of the typewriter is a pair of normally open spring blade contacts 310; and, when the bell crank 303 is rocked clockwise due to the operation of the cam unit 299, a stud 311 projecting upwardly from the arm of the bell crank 303 engages and closes the contacts 310 for a purpose which will appear fully hereinafter. The contacts 310 are closed during the time the carriage is being back spaced and when the latter operation is completed the contacts will return to their normal open position.

The tabulating mechanism for the typewriter is shown more clearly in Figs. 13, 14, and 15. Fig. 13 shows the tab key 218 and its related cam unit 312 which is operated in response to the actuation of the tab key lever 313, either by manually depressing the key 218 or by the energizing of a

solenoid 314 in response to the sensing of a tab code designation recorded in the record tape (see Fig. 20). The cam unit 312 is similar to the cam unit 233 shown at the left of the power roller 232 in Fig. 8 and, as will be readily understood, is operated by its related key lever 313 in the same manner as the operation previously described in connection with the cam units 233. The cam unit 312 is connected by a link 315 to one end of a rock lever 316 pivotally supported by the rod 229 and the other end of the lever 316 is connected by a link 317 with a lever 318 pivoted to a bracket mounted on the left-hand end of the fixed rail 242 and operatively connected to the tab lever 319 shown in Figs. 14 and 15.

The tabulating mechanism shown in Figs. 14 and 15 is the same as is fully disclosed in U. S. Patent No. 1,935,436 granted November 14, 1933, and operates in the same manner as the structure disclosed therein, with the exception that instead of providing removable tab stops like the one indicated at "4" in the last mentioned patent, a plurality of tab stops 320 are pivotally mounted on a stop bar 321 carried by the carriage 220 and are equal in number and correspond respectively, to the letter space positions in a line of typing. The latter type of pivoted tab stop may be selectively and individually set to be engaged by the tab lever 319 to stop the carriage at any related letter space position in the same manner as is disclosed in U. S. Patent No. 2,157,053, granted May 2, 1939. The operation and detail construction of the tabulating mechanism shown herein, is well known to those skilled in this art and can be readily understood by reference to the patents mentioned. Consequently, it will be needless duplication to describe the mechanism in full herein. It is considered sufficient for the purposes of the present disclosure, to state that the tab lever 319 is pivoted at 323 in such a manner that it has limited movement about an axis normal to the plane of Fig. 14 of the drawings. When the cam unit 312 is operated, the link 317 pulls the left-hand end of the tab lever 319 downward as viewed in Fig. 14, which will be toward the rear of the typewriter, which results in the moving of the stop 324 on the right-hand end thereof upward in Fig. 14 or toward the rear of the machine where it will intercept and engage the next selected one of the tab stops 320. When the latter engagement occurs, the tab lever 319 is moved back to the position shown and the escapement pawls 325 are released and thereby engage the rack 307 to stop the carriage 220 at the letter space position corresponding to the selected one of the tab stops 320 which was just engaged.

The several letter space positions where it is desired to stop the carriage by a tabulating operation, are determined during the preparation of the record tape and they are manually noted on the leading end of the tape in any suitable way so that when it is desired to transcribe the intelligence, such as a letter, from the prepared record tape, the tab stops 320 corresponding to the letter space positions noted on the tape are first set in the manner explained in the above-identified Patent No. 2,157,053. Then, when the tape is run through the reader, the typewriter carriage 220 will be automatically moved to the correct positions determined by the tab code designations in the tape and the position of the tab stop 320.

As shown in Fig. 14, two pairs of spring blade contacts 326 and 327, respectively, are arranged at the rear and left-hand end of the typewriter and are operated by the adjacent end of the tab

lever 319. The contacts may be mounted in any suitable manner on a fixed part of the typewriter. The contacts forming the pair 326 are carried by a fixed blade 328 and a movable spring blade 329, respectively, and the blade 329 is biased to move toward open position. The contacts forming the pair 327 are carried by a fixed blade 330 and a movable spring blade 331, respectively, and the blade 331 is biased to move toward closed position. As shown, the movable blades 329 and 331 are arranged adjacent to one another and are structurally connected by a member 332 for movement together in unison. The member 332 may be formed of any suitable insulation material. The end of the member contacts the left-hand end of the tab lever 319 and is held thereagainst by the inherent resiliency in the blades 329 and 331. The normal position of the parts is shown in Fig. 14. The contacts 326 are held by the member 332 and tab lever 319 in closed position and the contacts 327 are held thereby in open position. When the tab key lever 319 is operated by the energization of the solenoid 314, the link 317 will pull the left-hand end of the tab lever 319 downward, as viewed in Fig. 14, which is toward the front of the typewriter, and as a result, the inherent resiliency in the blades 329 and 331 will cause the member 332 to follow the tab lever and thereby open the contacts 326 and close the contacts 327. When the stop 324 engages the next pre-set tab stop 328, the tab lever 319 will be engaged and returned to the normal position shown and the contacts 327 will be moved to their normal open position and the contacts 326 moved to their normal closed position. The function of the contacts 326 and 327 will be described more fully hereinafter in connection with the wiring diagram shown in Figs. 19a and 19b.

The mechanism shown herein for returning the carriage to begin a new line of typing is well known to those skilled in the typewriter art. Attention is directed to U. S. Patent No. 2,104,559, granted January 4, 1938, and U. S. Patent No. 1,753,450, granted April 8, 1930, for a full disclosure of the structural details of the carriage return mechanism shown herein, the later granted patent being directed to the specific clutch shown herein for connecting the power roller to the drum about which the carriage return tape is wound.

Referring to Figs. 16 and 17, the carriage return key 218 is shown as mounted on a key lever 335 pivoted on the rod 229 and controlling the operation of a cam unit 336 which is similar in construction and operation to the previously described cam unit 233 shown at the right of the power roller in Fig. 8 hereof. A solenoid 337 is connected by a spring 338 to the key lever 335 and when energized, moves the key lever downward to effect operation of the cam unit 336. The latter is connected by a link 339 with the inner or left-hand end of a toggle lever 340 pivoted on a fixed stud 341 carried by a bracket 342 which is secured to a part 343 (Fig. 17) of the frame of the typewriter. The outer or right-hand end of lever 340 is connected by a toggle link 344 (Fig. 17) to one arm of a two-part lever 345 pivoted on a pin 346 which is carried by the lower end of a bracket 347 fixed on the typewriter frame part 343. Another arm 348 of the two-part lever 345 is disposed adjacent a clutch 349. As described fully in Patent No. 2,104,559, when lever 345 is rocked clockwise, as viewed in Fig. 17 herein, the clutch 349 connects the power roller 232 with a drum 350 about which one end

of a carriage return tape 351 is wound. The other end of the tape 351 is connected to a part of the typewriter carriage 220.

When the cam unit 336 is operated by energizing the solenoid 337 as just stated, or by manually depressing the key 218, the lever 340 is rocked counterclockwise as viewed in Fig. 17, and the toggle formed by the right-hand arm of lever 340 and the link 344 is straightened and thereby effects the just mentioned clockwise movement of two-part lever 345 to engage the clutch 349. The lever 340 is moved by the link 339 slightly past the dead center position of the toggle and thus the lever 340 and the associated parts are held in their clutch engaging position. Upon engagement of the clutch 349, the carriage 220 will be returned, i. e., moved to the right as viewed in Fig. 17, to begin a new line of typing.

At the same time the lever 340 is moved to engage the clutch in the manner just described, the inner or left-hand end of the lever 340 engages and moves downward one arm 352 of a bell crank 353 which is suitably pivoted by a pin 354 to a fixed part 355 of the typewriter frame. The bell crank 353 will thus be moved about its pivot pin and a second arm 356 thereof, through a connecting link 357, will move a lever 358 pivotally mounted on a pin 359, clockwise about its pivot; and the lever 358 through a link 360 will move a lever 361 which is pivoted on a pin 362 carried by the rail 242, counterclockwise about its pivot (see also Fig. 15). The lever 361 is formed with an arm 363 which when moved counterclockwise in the manner just stated, will be positioned within the path of travel of the left-hand marginal stop 364 of the typewriter. The stop 364 is mounted on a rack bar 366 carried by the typewriter carriage, and can be positioned thereon at any selected point corresponding to a letter space position of the carriage. Near the end of the return movement of the carriage and just before the marginal stop 364 engages a fixed lug 365 formed on the tab lever 319, to stop the carriage, the marginal stop 364 engages the top surface of arm 363 and thereby rocks the lever 361 clockwise. When the lever 361 is thus moved clockwise, motion is transmitted through the link 360, lever 358, and link 357 to rock the bell crank 353 so as to move its arm 352 upward to engage the lever 340 and thereby move the latter clockwise to break the toggle and move the two-part lever 345 counterclockwise which will effect disengagement of the clutch 349 and thereby disconnect the power roller 232 from the tape drum 350.

As indicated in Fig. 16, the carriage return cam unit 336 is provided with a downward extension 367 carrying a contact operating roller 368 which engages the intermediate movable spring blade 369 of a set of transfer contacts 370 suitably mounted on the typewriter. Upper and lower stationary blades 371 and 372 are arranged at opposite sides of the movable blade 369 and carry, respectively, contact points 373 and 374. The inherent resiliency of the blade 369 normally holds the latter in position where it engages the contact point 373 to hold closed a circuit controlled thereby. When the cam unit 336 is operated in the manner previously described, the roller 368 shifts the blade 369 from engagement with the normally closed point 373 to open the circuit controlled thereby, and effects engagement with the contact point 374 to close a circuit controlled by the latter. While the carriage is returning, the toggle lever 340 holds the

cam unit 336 in the shifted position and the latter holds the contact point 374 closed and the contact point 373 open. When the carriage returns to the point for beginning a new line of typing and the toggle is broken by the arm 352, the cam unit 336 returns to its normal position, shown in the drawings, and the blade 369 moves to open contact point 374 and to close the contact point 373. The purpose of the transfer contacts mechanically operated in the manner just explained by the cam unit 336 will be described presently.

Fig. 18 of the drawings, shows a portion of the rack bar 366 which is mounted on the typewriter carriage 220 and with the right hand marginal stop 376 mounted thereon and formed with a rearward extension 377 adapted to operatively engage a contact operating lever 378 when the typewriter carriage reaches a preselected letter space position determined by the position of the stop 377 (see also Fig. 8). In Fig. 18, the stop 376 and the direction of movement of the carriage and bar 366 is reversed with respect to Fig. 17, because Fig. 18 shows the parts as they appear when viewed from the back of the typewriter. The contact operating lever 378 is pivotally supported by a stud 379 projecting from the rear fixed part 380 of the typewriter and normally remains in the position shown in Fig. 18. The marginal stop 376 is shown in the position it occupies just as the extension 377 engages the lever 378 to move it clockwise. The lever 378 is formed with a central projection 381 which normally rests on an upper movable spring blade 382 of a set of normally open contacts suitably mounted on the typewriter. The set of contacts also comprise an intermediate movable spring blade 383 normally held in the position shown, and a lower stationary blade 384. The upper blade 382 is provided with a contact 385 on its under side, the intermediate blade with contacts 386 and 387 on opposite sides thereof, and the lower blade with a contact 388 on its upper side.

As stated, the rack bar 366 and right-hand marginal stop 376 are shown in the position they occupy just before closure of the contacts. A typing of another letter or the spacing of the carriage, will result in the movement of the rack bar one space and the consequent movement of the blade 382 a distance sufficient to close contacts 385 and 386. The typing of a second letter or the actuation of the typewriter space bar will move the carriage an additional space which will effect the movement of both the blades 382 and 383 to engage also contacts 387 and 388 and will thereby effect an electrical connection between all of the contacts. The circuits controlled by the contacts just described provide for the automatic return of the carriage at any selected point and will be presently described. As will presently appear, the apparatus disclosed herein provides for the control of the carriage return either from the record tape by energizing the solenoid as a result of sensing a selected code designation recorded in the tape, or carriage return may be effected by energizing the solenoid 337 as a result of the closure of the automatic margin control contacts 385, 386, 387, and 388 as just described.

As will be readily appreciated by those skilled in this art, the left-hand marginal stop 364 may be adjusted to any desired position on the rack bar 366 which is mounted on the typewriter carriage, so that the carriage will be stopped at any desired letter space position to begin a new line

of typing. Also, the right-hand marginal stop 376 (see Figs. 17 and 18) can be adjusted to fix the end of the line of typing at any desired point when automatic margin control is desired, or the stop 376 can be moved out of the way when it is desired that the right-hand margin be controlled by a carriage return code designation in the tape.

Referring now to the wiring diagram shown in Figs. 19a and 19b, it is noted that all of the electrical instrumentalities and circuit wires located within the reader 100 are shown diagrammatically in Fig. 19a, and this includes the relay translator mechanism previously referred to herein; and all of the electrical instrumentalities and circuit wires carried by the typewriter are shown in Fig. 19b. For the purposes of simplicity, the circuit wires of the reader which are connected, respectively, by the individual wires within the cable RT (Fig. 1) with corresponding circuit wires in the typewriter are shown as terminating at the right-hand margin of Fig. 19a in plug socket connections, designated, respectively as R1 to R56, inclusive. The corresponding circuit wires in the typewriter terminate at the left-hand margin of Fig. 19b in plug socket connections T1 to T56, inclusive. It is to be assumed that the plug sockets R1 to R56 are connected, respectively, to the plug sockets T1 to T56, inclusive, by the individual cable wires.

As stated above, the relay translator mechanism comprises the series of relays M1 to M6, inclusive, which, during each cycle of operation of the reader, are energized singly or in combination, as a result of the sensing of code hole designations in the record tape. The relay translator shown is a well known mechanism which, in response to the selective energization of its relay magnets in the manner just stated, sets up a number of circuit paths corresponding, respectively, to the code designations sensed. The relays M1 to M6, inclusive, control, respectively, the operation of one or more related transfer contacts which during each sensing cycle will be transferred, or left at normal position, so that the contacts may be connected in combinational series to establish the just mentioned circuit paths. As shown, the armature of relay M1 operates a pair of contacts M1-1; the armature of relay M2 operates two pairs of contacts M2-1 and M2-2; the armature of relay M3 operates four pairs of contacts M3-1 to M3-4, inclusive; the armature of relay M4 operates eight contacts M4-1 to M4-8, inclusive; the armature of relay M5 operates sixteen contacts M5-1 to M5-16, inclusive; and the armature of relay M6 operates thirty-two contacts M6-1 to M6-32, inclusive. These various relay controlled contacts are shown in their upper or normal position, which is the position they occupy when their related operating relays are deenergized. When any translator relay is energized, all of its related contacts transfer to the lower position.

In Fig. 19b the plug socket connections T1 to T48, inclusive, are shown as connected, respectively, by individual circuit wires with the solenoids which operate the character and functional key levers of the typewriter previously described. A legend appears adjacent each solenoid indicating the typewriter character or function corresponding thereto.

In Figs. 19a and 19b, all switches, solenoids, relays, contacts and associated parts are shown in the positions they normally occupy with no tape under the sensing gate 21 (Fig. 1) and with both

power switches 24 and 224 in open position. A source of 110 v. alternating current is indicated in Fig. 19a by the lead wires 400 and 401.

As stated previously, both the reader motor RM and the typewriter motor TM are operated when either the power switch 24 or the power switch 224 is in closed position. One side of the motor RM is permanently connected to the lead 400, and also one side of the motor TM is permanently connected to the lead 400 by a wire 402, plug socket connections R56 and T56, wire 403, and wire 404. Upon closing of switch 24, the other side of the motor RM is connected thereby to the other AC supply lead 401 by a wire 408, and the other side of the motor TM is connected to the supply lead 401 by a wire 409, plug socket connections R50 and T50 and wire 405. The closure of the switch 24 also energizes a rectifier transformer 406, one side of the primary being permanently connected to the supply lead 400, and the other side being connected by a wire 407 with the wire 408.

With one side of the motors RM and TM and transformer 406 being permanently connected to the lead 400 in the manner just explained, the closing of switch 224 also energizes the motors RM and TM and the transformer 406 as follows: from wire 401, wire 410, plug socket connections R55 and T55, wire 411, the switch 224, a wire 412, wire 413, and wire 405, to the other side of the motor TM; and through wire 405, plug socket connections T50 and R50, the wires 409 and 408, to the other side of motor RM and by wire 407 to the other side of the primary of transformer 406.

With the transformer 406 energized in the manner just explained, alternating current is supplied to the input terminals of the rectifier 415. The positive and negative DC output terminals of rectifier 415 are connected, respectively, to the D. C. (+) bus 416 and to the D. C. (-) bus 417. The coil of reader relay 420 is connected by wire 421 with the (+) bus 416 and by a wire 422 with the (-) bus 417, so that as long as the rectifier is supplied with alternating current, the relay 420 remains energized. When the latter is energized, the armature 423 thereof connects the (-) bus 417 to each of wires 431, 432, 433, 434, 435 and 436, which are, respectively, connected to the return sides of the six translator relays M1 to M6, inclusive.

With a record tape properly positioned under the gate 21 in the reader, the contacts 96 are closed by the pin 94 and the apparatus is ready for successively reading and transcribing the code designations in the tape onto the record sheet 221 in the typewriter. The tape sensing and feeding operation is started by depressing either the reader start switch 25 or the typewriter start 225. The reader start switch 25 is provided with two pairs of spring blade contacts 440, and 441, respectively, the contacts 440 being normally open and being closed upon depressing the start switch and the contacts 441 being normally closed, and being opened when the start switch 25 is depressed. The movable one of the normally open contacts 440 is connected by a wire 442, with the D. C. (+) bus 416. When contacts 440 are closed by depressing switch 25, direct current will flow from the (+) bus 416 through the wire 442, contacts 440, a wire 443, plug socket connections R53 and T53, a wire 444, the normally closed insert switch 227, a wire 445, plug socket connections T51 and R51, a wire 446, normally closed pick-up contacts 447 of a master control relay 448, a wire 449 to one side of a main coil 450 of such relay; 75

and, from the coil 450, through wire 451, the now closed contacts 96, a wire 452 to the (-) bus 417. When the master control relay is thus energized, the armature thereof moves to the right and thereby opens the pick-up contacts 447 and closes a pair of holding contacts 453, the latter being connected directly to the (+) bus 416 by a wire 454. The contacts 447 and 453 are of the overlapping type, that is, the holding contacts 453 make before the pick-up contacts 447 break. With the holding contacts 453 closed, direct current will flow through the holding circuit for the main coil 450 which is traced as follows: from the (+) bus 416, through the wire 454, contacts 453, wire 449 to the coil 450; and, from the latter, through the wire 451, contacts 96 and wire 452, to the (-) bus 417.

Contacts 455 also close when master control relay 448 is energized; and when the start switch 25 is released, the contacts 441 thereof again close and an energizing circuit for the clutch magnet CM is thereby established, which is traced as follows: from the D. C. (+) bus 416 through the plug socket connections R54 and T54, a wire 456, a wire 457, normally closed contacts 373 which are under the control of the carriage return cam unit 336, a wire 458, normally closed contacts 326 which are under the control of the tab lever 319, wire 459, the normally closed contacts 460 of the typewriter start switch 225, wire 461, plug socket connections T52 and A52, wire 462, the now closed contacts 455 of the master control relay 448, a wire 463, the now closed contacts 441 of start switch 25, wire 464, the clutch magnet CM, and from the latter through a wire 465, wire 451, the now closed contacts 96, and wire 452, to the (-) bus 417. The circuit just traced is hereinafter referred to as the clutch magnet circuit, and it is noted that such circuit can be broken by the opening of either the contacts 455, the contacts 373, or the contacts 326. With the clutch magnet CM energized, the operating shaft 35 of the reader is connected by the clutch 37 to the power shaft 31 and the successive tape feeding and sensing operations will begin in the manner fully explained hereinbefore.

The typewriter start switch 225 is connected in parallel with the start switch 25, and the operation of the apparatus may be started by depressing and releasing the switch 225 in the same manner as just described in connection with the switch 25. As shown, the switch 225 is provided with two pairs of spring blade contacts which are the normally closed contacts 460 mentioned above, and a normally open pair of contacts 467. One contact of the pair of contacts 467 is permanently connected to the D. C. (+) bus 416 through the wire 456 and plug socket connections T54 and R54. The other one of the pair of contacts 467 is connected by a wire 468 and a wire 469 with the normally closed insert switch 227 which, as explained previously in connection with switch 25, is connected to the D. C. (-) bus 417 through the wire 445, plug socket connections T51 and R51 pick-up contacts 447 of the master control relay, wire 449, coil 450, wire 451, contacts 96, and wire 452. Thus, with the apparatus at rest, by depressing the switch 225 to close the contacts 467, and open the contacts 460, a flow path for direct current is established through the pick-up contacts 447 and coil 450 of the master control relay 448, which, when energized, will close the holding contacts 453 and remain energized by the circuit previously traced. When the start switch 225 is released, contacts 460 are closed, which

establishes the energizing circuit for the clutch magnet CM through the now closed contacts 455 of the master control relay, which circuit was also traced above.

As described previously herein, when the reader shaft 35 commences to rotate, due to the energizing of the clutch magnet CM and the resulting engagement of clutch 37, the tape 10 is first spaced to move a record field into sensing position which is directly above the sensing pins S1 to S6, inclusive, and the field is sensed by the pins to determine the code hole designation therein. As an example, let it be assumed that the record field being sensed bears the code hole designation for the letter character "Y," which, as shown in Fig. 20, comprises code holes in positions 1, 3, and 5. As shown in Fig. 7, and as previously explained, the sensing of the code hole designation for the letter "Y" will result in the sensing pins S1, S3, and S5 moving upward through the code holes in the tape to close contacts C1, C3, and C5, respectively. The contacts C, C3, and C5 will close at approximately 130° of the revolution of shaft 35 and will remain closed until 325°, and the D. C. common contacts 104 are closed by the cam 102 at 142° and are opened again at 311°. With the contacts C1, C3, and C5 closed, and with the D. C. common contacts 104 closed, direct current will flow from the D. C. bus 416 through contacts 104, the contacts C1, C3, and C5 in parallel, and through wires 471, 473, and 475 to translator relay magnets M1, M3, and M5, respectively, and from the latter through wires 431, 433, and 435, respectively, to the D. C. (-) bus 417. With the relay magnets M1, M3, and M5 energized, their related contacts are transferred to the lower position. As the relays M2, M4, and M6 remain de-energized, their related transfer contacts will remain in their normal upper position.

With the transfer contacts of the translator in the position just stated, and when the cam 106 on the reader shaft 35 closes the A. C. common contacts 108 at 170° of the revolution, alternating current will flow through the circuit path established by the translator contacts to the solenoid 247 controlling the key lever for the letter "Y" on the typewriter, and, thereby, effect the operation of the related type bar in the manner previously explained. The established circuit path is traceable as follows: from the A. C. supply lead 400, a wire 477, contacts 108 now closed, a wire 478, contacts M1-1 in the lower position, a wire 479, contacts M2-2 in the position shown, a wire 480, contacts M3-3 in the lower position, a wire 481, contacts M4-6 in the position shown, a wire 482, contacts M5-11 in the lower position, a wire 483, contacts M6-22 in the position shown, a wire 484, the plug socket connections R33 and T33, a wire 485, solenoid 247 for actuating the key lever corresponding to the letter character "Y," a wire 486, and if the power switch 24 is closed, through the wires 413 and 405, plug socket connections T50 and R50, the wire 409, switch 24 to the A. C. supply wire 401. If instead, the switch 224 is closed, the circuit will include the wire 412, switch 224, wire 411, plug socket T55 and R55, and wire 410.

As long as the clutch magnet CM remains energized, and the contacts 96 are closed by the tape 10 at the reading station 20, the cycles of operation of the apparatus will be repeated. During each such cycle of operation, the tape will first be spaced to bring the new record field into sensing position, and such record field will then

be sensed to determine the code designation therein in the manner previously described. If the field sensed bears a character code designation, a spaced code designation, a shift code designation or a shift release code designation, the translator relays will be operated to establish an A. C. circuit path through the related solenoids to actuate the related key lever in the same manner as just explained in connection with the sensing of the code designation for the letter character "Y."

Provision is made herein for stopping the tape feeding and sensing operation when the code designation sensed is that corresponding to a carriage return, a back spacing or a tabulating operation, so that the typewriter will have time to complete such functional operations. Just as soon as these functional operations are completed, the tape feeding and sensing operation is automatically resumed so that a minimum of time is lost.

When the carriage return code designation is sensed, the sensing pin S4 closes contact C4, which, when the D. C. common contacts 104 are closed by the cam 102, provides for the flow of direct current through the translator relay M4, and thereby moves its related transfer contacts to the lower position; and, when the A. C. common contacts 108 are closed, alternating current will flow through an established circuit path including the translator relay contacts and the carriage return solenoid 337, to effect the return of the carriage in the manner previously described. This A. C. circuit path is traced as follows: from the supply line 400, through the wire 477, contacts 108, wire 478, contacts M1-1 in the position shown, contacts M2-1 in the position shown, contacts M3-1 in the lower position, contacts M4-1 in the lower position, contacts M5-2 in the position shown, contacts M6-3 in the position shown, wire 488, plug socket connection R4 and T4, wire 489, switch 490, the carriage return solenoid 337, wire 491, wire 492, plug socket connections T49 and R49, to one input terminal of a rectifier 493, and from the other input terminal of the rectifier through wire 409, power switch 24 to the A. C. supply wire 401. If the power switch 224 be closed, instead of switch 24, the A. C. supply wire 401 will be connected to the aforesaid other input terminal of the rectifier 493 by the wire 410, plug sockets R55 and T55, wire 411, switch 224, wires 412, 413, and 405, and plug sockets T50 and R50.

The D. C. positive output terminal of the rectifier 493 is connected by a wire 494 with a pair of contacts 495 of the master control relay 448 which are now closed as the relay 448 is energized, and a wire 496 connects the contacts 495 with one side of a bucking coil 497 of the relay 448, and the other side of the bucking coil 497 is connected by a wire 498 with the D. C. negative output terminal of the rectifier 493. The bucking coil 497 is wound in the opposite direction to the main coil 450 and when alternating current is supplied to the rectifier 493 by the above traced A. C. circuit path established due to the sensing of a carriage return code designation, the bucking coil 497 is energized by the D. C. circuit just traced, and the coil 497 is of sufficient strength to overcome the effect of main coil 450 and thereby cause the master control relay to drop out and open contacts 453, 455, and 495, and close again pick-up contacts 447. This will open the holding circuit for coil 450, and will also open the circuit holding the clutch magnet CM energized. The

opening of the clutch magnet circuit stops the tape feeding and sensing operation. The opening of contacts 455 will deenergize the bucking coil 487.

When the carriage return cam 338 is operated, the contacts 373 open and the contacts 374 close. The closure of contacts 374 establishes again the flow of direct current through the pick-up contacts 447 of the master control relay which is treated as follows: from the D. C. (+) bus 418, 5 plug socket connections R54 and T54, wire 458, wire 457, now closed contacts 374, wire 469, insert switch 227, wire 446, plug socket connections T41 and R51, wire 448, pick-up contacts 447, wire 449, coil 450, wire 451, contacts 98, and wire 452, to the (-) bus 417. As the circuit through the bucking coil 487 was broken when the contacts 455 opened, the reenergizing of the coil 450 through the pick-up contacts shifts the armature of the master relay to close the holding contacts 453, and thereby establish the holding circuit through the coil 450 previously traced.

However, when the cam unit 338 closed contacts 374 to energize again the master control relay 448 in the manner just explained, the contacts 373 were opened, and as the open contacts 373 are in the clutch magnet circuit previously traced, the closing of contacts 455 by the relay 448 will not energize the clutch magnet CM and start the tape feeding and sensing until the return of the carriage is completed, and the cam unit 338 is returned to its normal position and thereby opens contacts 374, and closes the contacts 373. Closure of contacts 373 will again establish the circuit through the clutch magnet CM and the tape feeding and sensing operation will continue from this point.

The sensing of a back space code designation provides for the energizing of translator relay M8, and the establishing of an A. C. circuit path through the translator contacts, the back space solenoid 297, and through the wire 491, wire 492, plug socket connections T49 and R49, through the rectifier 493, and from the latter to the A. C. supply wire 401, either by wire 409 and switch 24, or by sockets R50 and T50, wires 405 and 413, switch 224, wire 411, sockets T55 and R55 and wire 410. As before, the flow of current to the rectifier 493 energizes the bucking coil 487 and thereby drops out the master control relay 448 which opens the contacts 455 and deenergizes the clutch magnet CM. However, when the cam unit 299 operates the bell crank 303 (Fig. 14) to effect back spacing of the carriage, the contacts 310 are closed thereby and a D. C. circuit is established through the pick-up contacts 447 of the master control relay. This circuit is traced as follows: from the D. C. (+) bus 418, sockets R54 and T54, wires 458 and 457, contacts 310, wire 469, closed insert switch 227, wire 448, sockets T51 and R51, wire 446, pick-up contacts 447, coil 450, and from the latter to the (-) bus 417 through the wire 451, contacts 98, and wire 452. The back spacing of the carriage can be effected during the short interval of time between the dropping out of the master control relay to deenergize the clutch magnet CM and the reenergizing of the relay due to the closure of contacts 310. The clutch magnet circuit will be again closed as soon as the master control relay closes the contacts 455 and the reading and sensing of the tape will continue as before.

When a tab code hole designation is sensed in the tape, the translator relays M2, M3, M4, M5, and M6 are energized and shift their related trans-

fer contacts to establish an A. C. circuit path connecting the A. C. supply wires 400 and 401. This circuit path includes the transfer contacts, sockets R24 and T24, tab solenoid 314, wires 491 and 492, sockets T49 and R49, and the rectifier 493. As described previously, this will result in the dropping out of the master control relay 448 and the opening of the contacts 455 which open the clutch magnet circuit and thereby stop the reading and sensing of the tape. The actuation of the tab lever 319 (Fig. 14) also opens the contacts 326 which are in the clutch magnet circuit. The contacts 327 are closed by the actuation of the tab lever 319 and thereby establish a flow path for D. C. current through the pick-up contacts 447, and coil 450 of the master control relay, to energize again the relay 448; but, as the contacts 326 are open, the clutch magnet CM will not become energized until the completion of the tabulating operation, when the tab lever 319 returns to normal position and closes the contacts 326 in the clutch magnet circuit. When the latter happens, the tape sensing and reading continues as before.

Hereinbefore, the operation of the carriage return has been described as being effected under the control of a carriage return code designation in the tape. Provision is made in the apparatus disclosed for assuring the automatic return of the carriage in a case where the carriage return code designation has been inadvertently omitted from the tape. This operation is assured by the automatic margin control mechanism and contacts disclosed, in Fig. 18 and previously described herein. As will presently appear, the automatic margin control can also be used with a tape containing carriage return code designations and in such a manner as to change the length of the typed line in the copy from that originally provided for in the tape. Also the automatic margin control can provide for the return of the carriage from any selected point when the tape contains no carriage return code designation.

Considering first the operation of the apparatus when the carriage return code designation has been inadvertently omitted from the tape or when the prepared record tape contains no code designation for carriage return, the right-hand marginal stop 376 will be positioned at the selected letter space position on the rack bar 366, and the switch 500 (Fig. 19b) will be closed to render operative the automatic margin control circuits containing the contacts 385, 386, and the contacts 387, 388. When the carriage reaches a point where the member 377 on stop 376 just engages the lever 378 which is the position shown in Fig. 18, the typing of another character or the actuation of the spacing key lever will move the lever 378 a distance sufficient to close the contacts 385, 386. The closure of contacts 385, 386 establishes a path for the flow of alternating current traceable as follows: from the supply lead 400, the wire 402, plug sockets R56 and T56, wire 403, wire 501, switch 500 now closed, closed contacts 385 and 386, wire 502, wire 503, wire 492, plug sockets T49 and R49, the rectifier 493, wire 409, and switch 24 to the other A. C. supply lead 401. The flow of alternating current through the rectifier 493 energizes the D. C. bucking coil 487 and thereby drops out the master control relay 448 which opens the contacts 455 which are in the clutch magnet circuit, thereby deenergizing the clutch magnet CM and stopping the feeding and reading of the tape.

Before the clutch magnet becomes deenergized

in the manner just explained, an additional recording field will be sensed and the operating shaft 35 of the reader will continue to rotate until the revolution is completed. This will result in the typewriter being operated for one additional space which will cause the lever 378 to also close the contacts 387, 388. When the latter happens, a parallel A. C. circuit path will be established from the now closed contacts 387, 388, through wire 508, carriage return solenoid 337, wire 491, wire 492, plug sockets T49 and R49, rectifier 493, wire 499, power switch 24, and A. C. supply lead 401. The flow of current through the path just traced will result in the operation of the carriage return mechanism in the manner previously explained, but it will have no effect on the master control relay as the latter has already been deenergized by the closing of contacts 385, 386. The operation of the carriage return cam unit 336 will open and close the contacts 373 and 374, respectively, to pick up the master control relay and open up the clutch magnet circuit in the same manner as explained above in connection with the return of the carriage in response to the sensing of a code designation in the tape. Also, when the carriage is returned, cam unit 336 will open the contacts 374 and close the contacts 373 which will result in again establishing a flow of current through the clutch magnet CM and in continuing the tape reading and sensing operation from this point.

When the tape 10 has been prepared with code designations therein for carriage return and it is desired to provide a different length of typed line in the copy sheet 221, the switch 500 is closed and the switch 490 is shifted from the full line position shown to a position connecting the wire 489 with a wire 506 and the latter is connected at its other end to the control solenoid 247 for the space bar on the typewriter. The return of the carriage will then be under the control of the right-hand marginal stop 376 and will operate in the same manner as was just explained. When the carriage return code designation is sensed in the tape, the resulting A. C. impulse through the translator will be routed through the switch 490 in its changed position, and wire 506 to the space solenoid 247, which will cause the typewriter carriage to be spaced.

The sensing and feeding operation of the tape can be stopped at any time by depressing either the stop switch 26 on the reader, or the stop switch 226 on the typewriter. As will be noted, both the switch 26 and 226 are permanently connected to the A. C. supply lead 400, and the closure of either of these switches will provide for the flow of alternating current to the rectifier 493, and wire 499, and switch 24 to the other supply lead 401. This will energize the bucking coil 497, and thereby drop out the master control relay 448. From this point, operation can be resumed by depressing either the start switch 25 or 225.

Provision is also made for the stopping of the sensing and reading operations in response to a predetermined code hole designation in the tape. This operation is provided so as to permit the manual typing of an insert at any selected point on the copy sheet, as explained hereinabove. From Fig. 20, it is noted that the stop code designation is 1-2-4-5 and the sensing of this code designation will result in the translator establishing a flow path for alternating current traceable as follows: from the supply lead 400 through the translator contacts to a wire 507 which is connected to one input terminal of the rectifier 493 and from the other input terminal of the rectifier

5 through the wire 499, and power switch 24 to the other A. C. lead 401. Thus, the bucking coil 497 will be energized to drop out the master control relay. When this happens, the operator can open the insert switch 227 so as to prevent the closing of the pick-up circuit of the master control relay and can then manually operate the typewriter keyboard to type the desired insert on the copy sheet. When the latter is completed, the insert switch 227 can again be closed and the operation resumed by depressing either the start switch 25 or 225.

10 While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. 15 It is the intention therefore to be limited only as indicated by the scope of the following claims.

20 What is claimed is:

1. In apparatus for transcribing data onto a 25 copy sheet which has been recorded as code designations on a record strip, the combination of cyclically operated means for spacing the strip for sensing the code designations recorded there-in; translator mechanism for establishing, respectively, circuit flow paths corresponding, respectively, to the code designations sensed; a typewriter including character and functional actuators operable, respectively, by corresponding 30 circuit flow paths established by the translator; means including a master control relay and contacts closed thereby for maintaining the operation of the cyclically operated means; and means operable upon the beginning of a functional 35 operation of the typewriter requiring more time to complete than normally consumed by a character typing operation, for rendering the master control relay ineffective to maintain the operation of said cyclically operated means, and operable in response to the completion of such 40 functional operation to render said master control relay effective.

2. In apparatus for transcribing data onto a 45 copy sheet by means of a typewriter and under the control of a record strip bearing code designations corresponding, respectively, to character type elements and to the functional operations of the typewriter, the combination of mechanism for successively sensing the code designations on the strip; means including a master control relay effective to maintain continuous operation of said sensing mechanism; electro-mechanical devices selectively operable, respectively, to actuate said type elements and to effect the functional operations of said typewriter and including electrical instrumentalities operable to effect, respectively, certain of said functional operations requiring more time to complete their operation than normally consumed by a character typing operation; electrical means including translator mechanism operable in response to said sensing mechanism for establishing operating circuit paths through the electro-mechanical devices corresponding, respectively, to the code-designation sensed, and means effective upon the establishing of circuit flow paths through said instrumentalities for rendering ineffective said master control relay; and means operable in response to the completion of the typewriter functional operations effected by said instrumentalities for rendering said master control relay again effective

to maintain continuous operation of said sensing mechanism.

3. In apparatus for transcribing data onto a copy sheet by means of a typewriter and under the control of a record strip bearing code designations representing, respectively, the character type elements of the typewriter and the required functional operations of the typewriter, the combination of a plurality of character actuators effecting, respectively, the operation of the character type elements and functional actuators effecting, respectively, the functional operations of the typewriter; means including an operating shaft and sensing mechanism operated thereby for successively sensing the code designations on the record strip; a power shaft; a clutch operable to connect said power and operating shafts; a master control relay including a main coil effective to provide for maintaining engagement of said clutch and a bucking coil operable when energized to drop out said relay and render said main coil ineffective; means responsive to said sensing mechanism for effecting selective operation of the character and functional actuators corresponding, respectively, to the code designations sensed; and means operable upon the operation of a functional actuator corresponding to a functional operation requiring more time for its completion than normally consumed by a character typing operation, for energizing said bucking coil to render said main coil ineffective, and operable when the last-mentioned functional operation is completed to render said main coil again effective.

4. In apparatus for transcribing data onto a copy sheet by means of a typewriter and under the control of a record strip bearing code designations representing, respectively, the character type elements of the typewriter and the required functional operations of the typewriter, the combination of a plurality of character actuators effecting, respectively, the operation of the character type elements, and functional actuators effecting, respectively, the functional operations of the typewriter; means including an operating shaft and sensing mechanism operated thereby for successively sensing the code designations on the record strip; a power shaft; a clutch operable to connect said power and operating shafts; an electro-mechanical device effective upon a flow of electric current therethrough to provide for engagement of said clutch; a circuit connected to said electro-mechanical device; a master control relay comprising a main coil effective to close said circuit and a bucking coil effective when energized to render the main coil ineffective and to open said circuit; means for maintaining said main coil effective during normal operation; means responsive to said sensing mechanism for effecting selective operation of the character and functional actuators corresponding, respectively, to the code designations sensed; and means operable upon the operation of a functional actuator corresponding to a functional operation requiring more time for its completion than normally consumed by a character typing operation, for energizing said bucking coil to drop out said relay, and operable upon the completion of said last-mentioned functional operation for closing said circuit.

5. In apparatus for transcribing data onto a copy sheet by means of a typewriter and under the control of a record strip bearing code designations representing, respectively, the character type elements of the typewriter and the required functional operations of the typewriter, the com-

bination of a plurality of character actuators effecting, respectively, the operation of the character type elements, and functional actuators effecting, respectively, the functional operations of the typewriter; means including an operating shaft and sensing mechanism operated thereby for successively sensing the code designations on the record strip; a power shaft; a clutch operable to connect said power and operating shafts; an electrically operated device effective to engage and maintain engagement of said clutch; a clutch circuit for operating said device and including therein a pair of relay contacts and a pair of normally closed contacts; a master control relay including a main coil effective when energized to close said relay contacts, and a bucking coil effective when energized to open said relay contacts and deenergize said main coil; means responsive to said sensing mechanism for effecting selective operation of the character and functional actuators corresponding, respectively, to the code designations sensed; and means operable upon the operation of a functional actuator corresponding to a functional operation requiring more time for its completion than normally consumed by a character typing operation, to energize momentarily said bucking coil, to open said pair of normally closed contacts in said clutch circuit and to energize said main coil again, and operable when the last-mentioned functional operation is completed to close again said pair of normally closed contacts.

6. In transcribing apparatus, a typewriter including actuators for effecting operation of the type elements and for effecting the required functional operations of the typewriter; mechanism for successively sensing code designations recorded in a record tape and representing, respectively, said type elements and said functional operations; means responsive to said sensing mechanism for selectively operating the actuators corresponding, respectively, to the code designations sensed; means including a clutch effective when engaged to provide for continuing operations of said sensing mechanism; an electrically operated device operable to effect engagement of said clutch; a clutch circuit for operating said device and including therein a pair of relay contacts and a pair of normally closed contacts; a master control relay effective to maintain said relay contacts closed; electrical means operable in response to the initiation of certain of said functional operations for momentarily rendering said relay ineffective, and operable soon thereafter for opening said normally closed contacts and for rendering said relay again effective, and operable at the completion of said certain functional operations to close again said normally closed contacts.

7. In transcribing apparatus, a typewriter including actuators for effecting operation of the type elements and for effecting the required functional operations of the typewriter; mechanism for successively sensing code designations recorded in a record tape and representing, respectively, said type elements and said functional operations; means responsive to said sensing mechanism for selectively operating the actuators corresponding, respectively, to the code designations sensed; means including a clutch effective when engaged to provide for continuing operations of said sensing mechanism; an electrically operated device operable to effect engagement of said clutch; a clutch circuit for operating said device and including therein a pair of relay con-

tacts and a pair of normally closed contacts; a master control relay including a main coil effective when energized to close said relay contacts, and a bucking coil effective when energized to open said relay contacts and deenergize said main coil; and means operable upon the initiation of a certain of said functional operations for momentarily energizing said bucking coil, and operable immediately thereafter for opening said normally closed contacts and for energizing again said main coil, and operable upon the completion of said certain functional operation for closing again said normally closed contacts.

8. In transcribing apparatus, a typewriter including actuators for effecting operation of the type elements and for effecting the required functional operations of the typewriter; mechanism for successively sensing code designations recorded in a record tape and representing, respectively, said type elements and said functional operations; means responsive to said sensing mechanism for selectively operating the actuators corresponding, respectively, to the code designations sensed; an electrically controlled device effective upon a flow of current thereto to provide for continuing operations of said sensing mechanism; a circuit for operating said device and including relay contacts and normally closed contacts; a master relay effective to maintain said relay contacts closed; and means responsive to the initiation of certain of said functional operations for rendering said relay ineffective, and operable immediately thereafter for opening said normally closed contacts and rendering said relay again effective, and operable when said certain functional operations are completed for closing again said normally closed contacts.

9. In transcribing apparatus, a typewriter including actuators for effecting operation of the type elements and for effecting the required functional operations of the typewriter and including a carriage return actuator for returning the typewriter carriage to begin a new line of typing; mechanism for successively sensing code designations recorded in a record tape and representing, respectively, said type elements and said functional operations; means responsive to said sensing mechanism for selectively operating the actuators corresponding, respectively, to the code designations sensed; an electrically controlled device effective upon a flow of current thereto to provide for continuing operations of said sensing mechanism; a circuit for operating said device and including relay contacts and normally closed contacts; a master relay effective to maintain said relay contacts closed; and means responsive to the operation of said carriage return actuator for rendering said relay ineffective and operable immediately thereafter to open said normally closed contacts and for rendering said relay again effective, and operable upon a completion of the carriage return operation for closing again said normally closed contacts.

10. In transcribing apparatus, a typewriter including actuators for effecting operation of the type elements and for effecting the required functional operations of the typewriter and including a back space actuator operable to effect the back spacing of the typewriter carriage; mechanism for successively sensing code designations recorded in a record tape and representing, respectively, said type elements and said functional operations; means responsive to said sensing mechanism for selectively operating the actuators corresponding, respectively, to the code designations sensed; an

electrically controlled device effective upon a flow of current thereto to provide for continuing operations of said sensing mechanism; a circuit for operating said device and including relay contacts; a master relay effective to main said relay contacts closed; and means operable simultaneously with the actuation of said back-space actuator for rendering said master relay ineffective, and operable soon thereafter and in response to the back spacing operation of the carriage for rendering said relay again effective.

11. In transcribing apparatus, a typewriter including actuators for effecting operation of the type elements and for effecting the required functional operations of the typewriter; mechanism for successively sensing code designations recorded in a record tape and representing, respectively, said type elements and said functional operations; means responsive to said sensing mechanism for selectively operating the actuators corresponding, respectively, to the code designations sensed; an electrically operated device for starting and maintaining operation of said sensing mechanism; a circuit for operating said device and including a pair of normally closed start-switch contacts and a pair of normally open relay contacts; a master relay including a coil operable when energized to close said relay contacts and to close a pair of normally open holding contacts; an energizing circuit for said relay coil including a pair of normally open start-switch contacts; a holding circuit for said relay coil including said holding contacts closed by said relay; and a start switch operable when moved from normal position to open said normally closed start-switch contacts and to close the normally open start-switch contacts in the energizing circuit, and operable when released to return to normal position and thereby to open the contacts in the energizing circuit and to close again the normally closed switch contacts.

12. In transcribing apparatus, a typewriter including a carriage for holding a copy sheet, carriage return mechanism, actuators for effecting operation of the type elements and for effecting functional operations of the typewriter, and a device for operating the carriage return mechanism; mechanism for sensing code designations recorded in a record tape and representing, respectively, said type elements and said functional operations of the typewriter; means responsive to said sensing mechanism for selectively operating the actuators corresponding to the code designations sensed; control means effective to start and maintain continuous operation of said sensing mechanism; adjustable margin means operable in response to said carriage reaching any selected one of a plurality of letter space positions for actuating said carriage return device; and means operable upon operation of said last named means for rendering said control means ineffective and operable when the carriage return operation is completed to render said control means again effective.

13. In transcribing apparatus, a typewriter including a carriage for holding a copy sheet, carriage return mechanism, actuators responsive to operating impulses for effecting operation of the type elements and for effecting the functional operations of the typewriter and including a spacing actuator for spacing the carriage, a carriage return actuator for actuating said carriage return mechanism, and adjustable margin means operable in response to the carriage reaching any selected one of a plurality of letter space posi-

tions; mechanism for sensing code designations recorded in a record tape and representing, respectively, said type elements and said functional operations; means responsive to the sensing of code designations representing, respectively, the type elements and said functional operations, for transmitting operating impulses to the corresponding actuators; means rendered effective at the selection of the operator for transmitting the carriage return operating impulses to the space actuator; a second means rendered effective at the selection of the operator and operable in response to said adjustable margin means for transmitting an operating impulse to said carriage return actuator when said carriage reaches a selected letter space position; master control means effective to start and maintain continuous operation of said sensing mechanism; and means operable upon the operation of said carriage return actuator, for rendering said master control means ineffective, and operable when the carriage return operation is completed for rendering said master control means again effective.

14. In transcribing apparatus, a typewriter including actuators for effecting operation of the type elements and for effecting the required functional operations of the typewriter; mechanism for successively sensing code designations recorded in a record tape and representing, respectively, said type elements and said functional operations; means responsive to said sensing mechanism for selectively operating the actuators corresponding, respectively, to the code designations sensed; an electrically controlled device effective upon a flow of electric current thereto to provide for continuing operations of said sensing mechanisms; a circuit for operating said device and including therein a pair of relay contacts and a pair of normally closed contacts; a master con-

trol relay including a main coil effective when energized to close said relay contacts, and a bucking coil effective when energized to open said relay contacts and deenergize said main coil, and means operable upon the initiation of said functional operations for momentarily energizing said bucking coil, and operable immediately thereafter for opening said normally closed contacts and for energizing said main coil and operable upon the completion of said certain functional operations for closing again said normally closed contacts.

15. In transcribing apparatus, a typewriter including actuators for effecting operation of the type elements and for effecting the required functional operations of the typewriter and including a tab actuator for effecting tabulating operations of the typewriter carriage; mechanism for successively sensing code designations recorded in a record tape and representing respectively, said type elements and said functional operations; means responsive to said sensing mechanism for selectively operating the actuators corresponding, respectively, to the code designations sensed; an electrically controlled device effective upon a flow of current thereto to provide for continuing operations of said sensing mechanism; a circuit for operating said device and including a pair of relay contacts and a pair of normally closed contacts; a master relay effective to maintain said relay contacts closed; and means responsive to the operation of said tab actuator for rendering said relay ineffective and operable immediately thereafter to open said normally closed contacts and for rendering said relay again effective, and operable upon a completion of the tabulating operation of the carriage for closing again said normally closed contacts.

HENRY L. THOLSTRUP.

CERTIFICATE OF CORRECTION.

Patent No. 2,378,371.

June 12, 1945.

HENRY L. THOLSTRUP.

It is hereby certified that error appears in the printed specification of the above numbered patent requiring correction as follows: Page 13, second column, line 27, claim 1, for the words "the strip" read -- the strip and--; page 15, second column, line 5, claim 10, for "main" read --main--; and that the said Letters Patent should be read with this correction therein that the same may conform to the record of the case in the Patent Office.

Signed and sealed this 18th day of September, A. D. 1945.

tions; mechanism for sensing code designations recorded in a record tape and representing, respectively, said type elements and said functional operations; means responsive to the sensing of code designations representing, respectively, the type elements and said functional operations, for transmitting operating impulses to the corresponding actuators; means rendered effective at the selection of the operator for transmitting the carriage return operating impulses to the space actuator; a second means rendered effective at the selection of the operator and operable in response to said adjustable margin means for transmitting an operating impulse to said carriage return actuator when said carriage reaches a selected letter space position; master control means effective to start and maintain continuous operation of said sensing mechanism; and means operable upon the operation of said carriage return actuator, for rendering said master control means ineffective, and operable when the carriage return operation is completed for rendering said master control means again effective.

14. In transcribing apparatus, a typewriter including actuators for effecting operation of the type elements and for effecting the required functional operations of the typewriter; mechanism for successively sensing code designations recorded in a record tape and representing, respectively, said type elements and said functional operations; means responsive to said sensing mechanism for selectively operating the actuators corresponding, respectively, to the code designations sensed; an electrically controlled device effective upon a flow of electric current thereto to provide for continuing operations of said sensing mechanisms; a circuit for operating said device and including therein a pair of relay contacts and a pair of normally closed contacts; a master con-

trol relay including a main coil effective when energized to close said relay contacts, and a bucking coil effective when energized to open said relay contacts and deenergize said main coil, and means operable upon the initiation of said functional operations for momentarily energizing said bucking coil, and operable immediately thereafter for opening said normally closed contacts and for energizing said main coil and operable upon the completion of said certain functional operations for closing again said normally closed contacts.

15. In transcribing apparatus, a typewriter including actuators for effecting operation of the type elements and for effecting the required functional operations of the typewriter and including a tab actuator for effecting tabulating operations of the typewriter carriage; mechanism for successively sensing code designations recorded in a record tape and representing respectively, said type elements and said functional operations; means responsive to said sensing mechanism for selectively operating the actuators corresponding, respectively, to the code designations sensed; an electrically controlled device effective upon a flow of current thereto to provide for continuing operations of said sensing mechanism; a circuit for operating said device and including a pair of relay contacts and a pair of normally closed contacts; a master relay effective to maintain said relay contacts closed; and means responsive to the operation of said tab actuator for rendering said relay ineffective and operable immediately thereafter to open said normally closed contacts and for rendering said relay again effective, and operable upon a completion of the tabulating operation of the carriage for closing again said normally closed contacts.
